UNITED STATES PATENT OFFICE

108,508

DESIGN FOR A STERILIZING UNIT OR SIMILAR ARTICLE

Henry M. Finn, Malden, and Max Laven, Boston,
Mass.

Application August 25, 1937, Serial No. 71,326

Term of patent 7 years

To all whom it may concern:

Be it known that we, Henry M. Finn and Max Laven, citizens of the United States and residents of Malden and Boston, respectively, in the Commonwealth of Massachusetts, have invented a new, original, and ornamental Design for a Sterilizing Unit or Similar Article, of which the following is a specification, reference being had to the accompanying drawing, forming part thereof.

Fig. 1 is a front elevational view of a sterilizing unit or similar article showing our new design.

Fig. 2 is a side elevational view.

Fig. 3 is a top plan view thereof.

The shading in the drawing represents contrasting colors but no particular color being represented.

What we claim is:

The ornamental design for a sterilizing unit or similar article substantially as shown and described.

HENRY M. FINN.
MAX LAVEN.
